United States Patent Office.

AARON MARDEN AND AARON H. BURGESS, OF PHILADELPHIA, PENN-SYLVANIA.

Letters Patent No. 66,032, dated June 25, 1867.

IMPROVEMENT IN NAIL-EXTRACTORS.

The Schedule referred to in these Letters Patent and making part of the same.

TO ALL WHOM IT MAY CONCERN:

Be it known that we, AARON MARDEN and AARON H. BURGESS, of the city and county of Philadelphia, and State of Pennsylvania, have invented a new and improved Nail-Extractor; and we do hereby declare the following is a full, clear, and exact description thereof, reference being had to the accompanying drawings, and to the letters of reference marked thereon.

The nature of our invention consists in making an implement for drawing nails from boxes. This instrument indents the wood and grasps the head of the nail at the same time; then, by a motion of the handle, the nail is pulled clean out almost perpendicularly.

To enable others skilled in the art to make and use our invention, we will proceed to describe its construction and operation.

Figure 1 is a plan.

Figure 2 is a section.

Similar letters in each figure refer to the same parts.

The instrument is made of a pair of jaws, D D, jointed at the top, and tapering towards the bottom. They are fitted into a tapering mortise, B, in one end of a handle, A. The part of the handle by this mortise is arched, and bears on a foot, C, and a fulcrum, C'; this arching allows the operator to see how to place the jaws directly over the nail-head. The jaws D are jointed at the top by a pin, e, fitting half-way into each, and a link, F, is fastened to each jaw by a pin, g. The ends of the jaws D are obtusely pointed at d d, and the inside surface is serrated to take a firm hold of the nail-head. At d' the jaw is indented or recessed, to accommodate the nail-head if the points d should be driven below it. h is a small coiled spring to separate the jaws D. Pins K' are driven through the mortise B, just above the hooks K, to prevent the jaws falling out of the handle; at the same time they allow a free motion of the jaws up and down a short distance. The jaws D are made slightly tapering in width, and smallest at the bottom, so that when in position they rest upon the lower part a' of the mortise B, which said mortise diverges at a greater angle than the said jaws. M is the wood from which the nail N is to be drawn; and when the instrument is in position for operating on the nail, as in fig. 2, the points of the jaws d, the foot C, and the fulcrum C' are all about on a line. About three inches from C' is another fulcrum, C''.

The operation of the instrument is this: The jaws D are placed over the nail, as in fig: 2, the handle resting on the points C and C'. The top ends of the jaws are then struck with a mallet, which forces them downwards, indenting the wood on each side of the nail, and at the same time (by the wedge-shaped form of the jaws) the points d are brought nearer together, and grasp the nail-head with great force. The end of handle A being now pressed downwards, a powerful leverage is obtained upon the fulcrum C', which starts the nail; the other fulcrum C'' now bears upon the wood, and the distance from the jaws to the fulcrum C'' being greater, the nail is drawn clean out, almost perpendicularly. It is not of much consequence whether the nail-head comes above the recess d' or not, as the construction of the wedge-shaped jaws gives such a powerful gripe that the nail can be drawn even if it has no head at all.

We do not restrict ourselves to the use of the particular spring h shown; nor to the pins K' for retaining the jaws in the mortise, as a single pin working in a perpendicular slot would answer the purpose; nor to the particular form of the top joint e, as it might be made like the joint of a pair of compasses, or other joint well known to machinists, the only requisite being that it must be strong enough to communicate the blow of the mallet from one to the other, if the mallet should not fall equally upon both jaws; and it must also allow the points d to open and shut a small distance.

What we claim as our invention, and desire to secure by Letters Patent, is—

We claim the jaws D D, when constructed with slightly tapering sides, hinged together at the top, and having an intervening spring, which jaws rest in a corresponding tapering mortise, B, in the handle A, and operate together in the manner substantially as described, and for the purpose specified.

AARON MARDEN,
AARON H. BURGESS.
